COMBINED FIRE HYDRANT AND DRINKING FOUNT

Filed Aug. 24, 1926

Fig. 1.

UNITED STATES PATENT OFFICE.

CARL J. LINDMARK, OF WARREN, PENNSYLVANIA.

COMBINED FIRE HYDRANT AND DRINKING FOUNT.

Application filed August 24, 1926. Serial No. 131,264.

This invention relates to combined fire hydrants and drinking fountains.

One object is to provide a hydrant of this class having connection with a water main, 5 the pressure in the main being controllable by means, readily accessible at one side of the hydrant, to admit the flow of water to hose lines of different sizes, which may be easily and quickly coupled to corresponding outlets 10 also located on the sides of the hydrant; and at the same time to provide, in combination with the above, a drinking fountain having constant connection with the lower end of the hydrant, below the usual cut-off valve, so as to 15 insure a steady flow of water, properly reduced by regulating means, to supply fresh drinking water to the public.

Another object is to provide a drinking fountain, in connection with a fire hydrant, which 20 is located at the highest point of said hydrant, to be most easily reached by the user, and to arrange the parts in such manner as not to interfere with the use of the hydrant in cases of fire, the parts of the combination device being such as to permit the same to be easily 25 assembled and properly adjusted for continued use without requiring further care, attention, or manipulation.

A full and complete understanding of the 30 invention may be obtained from a consideration of the following detailed description, taken in connection with the accompanying drawing forming a part of this specification; it being understood that while the drawing 35 shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:

45 Figure 1 is a vertical, longitudinal sectional view through the combined fire hydrant and drinking fountain.

Figure 2 is an enlarged longitudinal section through the cut-off valve and stem.

50 Figure 3 is an enlarged transverse sectional view, taken on the line 3—3 of Figure 1 and looking in the direction of the arrows.

Figure 4 is a similar view taken on the line 4—4 of Figure 1, but looking in the opposite 55 direction, as indicated by the arrows.

The preferred embodiment of the invention 60 comprises an elongated body or barrel 1, formed of suitable cast metal, said barrel being normally open at each end and provided, at its lower end, with an outstanding, annular flange 2 suitably apertured for connection by bolts with the flanged upper end of an elbow 3, having the usual socket 4 for connection with a service pipe leading from a main (not shown). 65

The lower end of the barrel is provided with 70 interior threads into which there is screwed a removable and adjustable valve seat 5, which is provided with an integrally-formed, inwardly-extending arm 6 which may serve 75 as means for connection with a specially formed, elongated wrench or turning tool to seat the valve in position, to adjust the same, or to remove it from its seat, for the purpose of repair or replacement.

The arm 6 is suitably apertured for the 80 reception of the upstanding tubular portion 7 of an ordinary ball valve 8 which is adapted to contact at its upper, tapered peripheral portion with the lower, correspondingly-tapered portion of the valve seat 5, when the valve is actuated to open and close in a manner to be explained.

85 Adjacent to its upper end, the barrel is provided with one or more outlets 1^a, which may be of a size to connect with fire hose to be supplied by the pressure from the main, at full, uninterrupted force, when the valve is open and, arranged above said connections are other connections 1^b of a smaller size to be used 90 in connection with smaller hose for other purposes.

The barrel 1 is provided at its upper end with an outstanding, annular flange 9 having a plurality of spaced bolt openings, and the upper terminal of the barrel is extended slightly above the flange and is formed into an annular seat 10 for the reception of a closure disk 11, which snugly fits within and on the seat, with a suitable gasket interposed to effectually seal the upper end of the barrel. 100

The closure disk 11 is provided at its center with a depending gland socket 12 for the reception of suitable packing, and the bottom wall of the socket is apertured to receive a 105 vertically-slidable valve stem 8^a, which is threaded into the upper end of the aforesaid extension or tubular portion 7. This stem is locked to the portion 7 by a suitable transverse pin, as shown in Figure 2 of the draw- 110

ing, and the said portion 7 is likewise locked or pinned to the clamping element of the valve proper, so as to avoid becoming unscrewed during the operation of the valve, in a manner 5 to be described.

A gland 13 is screwed into the upper part of the socket 12, and is likewise apertured for the reception of the valve stem 8^a, which is extended considerably above the upper face 10 of the closure disk 11.

Surmounting the upper end of the barrel 1 is a hollow dome-shaped cap 14, formed of cast metal and having an internal diameter to fit over the periphery of the upper flange 9 of the barrel. Spaced slightly above the lower peripheral edge of the cap 14, is an intermediate flange 15, the inner, marginal portions of which bear upon the marginal portions of the closure disk and are adapted to 20 hold the latter tightly in position upon the barrel.

The flange 15 is reinforced, at intervals, by radially-disposed webs 16, and said flange is provided with apertures aligned with the apertures in the flange 9 of the barrel and adapted to receive tie bolts 17, the nuts of which adjustably bear against the lower face of the flange 9, while the headed, upper ends of the bolts are seated within depressed seats 18 30 formed in the marginal portions of the upper wall 19 of the cap 14.

The upper wall 19 of the cap is of concavo-convex formation, and is provided at its center with a depending collar or enlargement 20 which extends slightly above the said wall 19, and the same is provided in its upper portion with a threaded bore or passageway into which is threaded a retaining nut 21 having the usual polygonal head for adjusting the 40 same in the said threaded seat.

An elongated, tubular-shaped actuating nut 22 extends from the aforesaid gland 13, upwardly and through the center of the cap, the said nut having an enlarged intermediate 45 portion and round in cross section where traversing a corresponding opening 22^a in the aforesaid collar or enlargement 20 to permit said nut to freely turn in the cap. In order to prevent any longitudinal movement of the 50 nut 22, the same is provided with an annular flange 23 resting in the bottom of the threaded bore or passageway to be held therein by the pressure of the aforesaid retaining nut 21.

The upper end 24 of the elongated nut 22 55 is polygonal in cross section and extends somewhat above the upper face of the retaining nut 21, and a bevelled pinion 25 is mounted thereon to turn the nut 22 for a purpose to be explained, a washer 26 being preferably 60 interposed between the lower face of the pinion and the upper face of the nut 21.

Bearing upon the upper face of the pinion 25 and adapted to hold the same upon the upper end of the actuating nut, is a depending 65 collar 27 located at the center of an over-

flow basin 28, which is likewise formed of thin cast metal, and is supported in superimposed relation above the cap of the barrel.

Depending legs 29 are preferably formed integrally with the basin and are arranged in position to fit within the aforesaid depressed seats 18 of the cap, said legs having inwardly-turned feet 30 which are likewise apertured for the reception of the headed ends of the aforesaid tie bolts 17, which thus serve to 70 hold all the parts rigidly together.

The legs are all strengthened by triangular webs 31, and the basin is provided, in line with one of the legs, with an upwardly-offset portion 32 to form a housing, said leg being 75 provided with a horizontally-disposed, tubular bearing 33, arranged beneath the housing 32 and adapted to receive a short shaft 34, the latter being held from outward, longitudinal movement in the bearing by means 80 of a pin 34^a and a suitable washer bearing 85 against the inner end of the said bearing.

The inner end of the short shaft is reduced as shown at 35, and the same is rotatably mounted in a suitable horizontal 90 bearing opening formed in the inner wall of the housing 32, and joined integrally with said inner wall is a vertically-disposed tubular gland socket 36 arranged centrally within in the basin, as clearly shown in Figure 1 of 95 the drawing. Between the reduced end 35 and the shaft proper, there is a polygonal portion 37 on which is mounted a vertically-disposed, bevelled pinion 38 in meshing relation with the pinion 25, and adapted to rotate 100 the latter when the short shaft 34 is turned by means of a suitable wrench or other tool which may be readily applied to the wrench-head 39 formed on the extended, outer end of the said shaft.

The gland socket 36 is internally threaded 105 at its upper end for the reception of a gland nut 40, and it will be seen, by reference to Figure 1 of the drawing, that the valve stem 8^a carrying the main cut-off valve at its lower end, passes upwardly through the gland nut 13, thence through the elongated actuating nut 22, where the said stem is provided with complementary threads 41, and then upwardly, at somewhat reduced diameter, through 110 the upper gland nut 40, within the basin 28. It will thus be seen that, by rotating the short shaft 34, by means of a wrench, or the like, movement is imparted to the nut 22 and the latter, being free to rotate within the seat 115 in the top of the dome or cap, and being held from longitudinal movement by means of the flange 23, will cause the valve stem and the valve, by reason of the threaded engagement 41, to be raised or lowered, depending 120 on the direction of rotation of the short shaft 34.

The reduced upper end 42 of the valve stem is provided with a relatively small bore 125 or passageway 43, which is extended down 130

through the lower portion of the stem to the lower end thereof so as to be in constant communication with the water, under pressure, below the valve and to insure a steady and continuous flow of fresh water to the upper end of the tubular valve stem.

Mounted on the upper end of the valve stem and substantially flush with the peripheral edge of the basin 28, is a mouthpiece 44 through which the passage 45 forms a continuation of the passage through the stem, and the constant flow of water through the mouthpiece is regulated by means of an adjustable screw 46 passing through the side of the mouthpiece and intersecting the passageway 45 in a transverse direction in the same manner as a needle valve.

At substantially the lowest point in the basin and adjacent to the central, upstanding socket 36 a screw threaded opening 47 is provided and into the same is screwed the upper end of a relatively small drain pipe 48 which passes downwardly to the ground, to connect with a sewer or gutter, said tube being bent to conform to the shape of the cap 14 and the barrel 1.

From the foregoing it will be seen that a combined fire hydrant and drinking fountain has been provided, which will readily permit of the application of fire hose or other smaller hose in the case of fire or other emergency, the valve controlling means being always readily accessible, while at the same time a steady supply of fresh drinking water is allowed to flow out of the mouthpiece, such flow being easily regulated so as not to overflow the basin, the excess water being constantly carried off by the drain pipe.

What is claimed is:

1. A combined fire hydrant and drinking fountain comprising an upstanding barrel having a pressure-main connection and hose connections, a detachable cap secured to the barrel, a main cut-off valve at the lower end of the barrel, a valve stem extending up through said cap and having a continuous passage therethrough communicating constantly with the main, controllable means mounted on the cap and connected with the valve stem to open and close the valve, a basin mounted on the cap above the controllable means and surrounding the upper end of the valve stem, a mouthpiece mounted on the latter, and a drain pipe connected to the basin.

2. A combined fire hydrant and drinking fountain comprising an upstanding barrel having a pressure-main connection and hose connections, a closure disk at the top of the barrel, a main cut-off valve at the lower end of the barrel, a valve stem extending from said valve up through said closure disk and having a continuous passage therethrough communicating constantly with the main, controllable means connected with the valve stem

to open and close the valve, a basin mounted above the controllable means and surrounding the upper end of the valve stem, a mouthpiece mounted on the valve stem to provide for a continuous flow of water, and a drain pipe connected to the basin.

3. A combined fire hydrant and drinking fountain comprising an upstanding barrel having connection with a pressure main at its lower end and provided with hose connections near its upper end, a valve-seat located above the main connection, a valve adapted to be seated therein and having a tubular valve stem extending up above the top of the barrel and having external threads, a closure disk fitting the upper end of the barrel and having a gland for the valve stem, a hollow cap connected to the barrel and bearing on the closure disk, a socket formed in the cap, a nut seated in the socket and engaging the threads of the stem, an overflow basin mounted above the cap and supported by the same in surrounding relation to the valve stem, means carried by the basin for turning the nut to open and close the valve, a mouth piece mounted on the upper end of the stem and having means for regulating the flow of water therethrough, and a drain pipe connected to the basin and passing down one side of the barrel.

4. A combined fire hydrant and drinking fountain comprising an upstanding barrel adapted to be connected to a pressure main, a cut-off valve having a tubular stem extending above the top of the barrel and provided with external threads, a dome-shaped cap detachably mounted on the barrel and having a stepped socket surrounding the stem, an elongated nut having a flange seated in the stepped socket, a retaining nut threaded in the socket and bearing on said flange to prevent longitudinal movement of the elongated nut, said nut having internal threads engaging the threads of the valve stem to raise and lower the latter when the said nut is turned, an overflow basin located above the cap and having a gland surrounding the valve stem, legs depending from the basin and connected to the cap for supporting said basin, means carried by one of the legs and connected to the elongated nut for turning the latter to cause the opening and closing of the cut-off valve, a mouthpiece screwed to the upper end of the tubular valve stem, a set screw mounted in the mouthpiece for regulating the flow of water therethrough, and a drain pipe connected to the bottom of the overflow basin.

5. A combined fire hydrant and drinking fountain comprising an upstanding barrel adapted to be connected to a pressure main, a cut-off valve having a tubular stem extending above the top of the barrel and provided with external threads, a dome-shaped cap detachably mounted on the barrel and having a stepped socket surrounding the stem, an

elongated nut having a flange seated in the stepped socket, a retaining nut threaded in the socket and bearing on said flange to prevent longitudinal movement of the elongated nut, said nut having internal threads engaging the threads of the valve stem to raise and lower the latter when the said nut is turned, said elongated nut extending above the retaining nut and provided with a bevel pinion, an overflow basin located above the cap and having a gland surrounding the valve stem, the lower portion of the gland bearing on the said pinion, legs depending from the basin and detachably connected to the cap, a horizontal, tubular bearing formed on one of the legs, an actuating shaft mounted in said bearing and having a polygonal outer end for engaging a wrench, a bevel pinion mounted on the inner end of the shaft and engaging the first pinion for turning the elongated nut.

6. A combined fire hydrant and drinking fountain comprising an upstanding barrel having and outstanding flange at its upper end,

a vertically-movable cut-off valve located in the lower end of the barrel, a closure disk seated on the open upper end of the barrel and having a central gland, a tubular valve stem extending through said gland, a dome-shaped cap located over the upper end of the barrel and having an intermediate, inwardly-extending flange bearing upon the disk, radially disposed seats formed in the top of the cap, a basin located above the cap, integrally-formed legs depending from the basin and having feet fitting in said seats, bolts traversing the feet, the seats, the intermediate flange and the barrel flange to hold the parts together and form a water-tight joint between the closure disk and the barrel, said cap and basin having openings for the tubular valve stem to extend through, and means carried by one of the legs to raise and lower the valve stem.

In testimony, that I claim the foregoing as my own, I have hereto affixed my signature.

CARL J. LINDMARK.
